BY
Warren L. House
His ATTORNEY.

UNITED STATES PATENT OFFICE

ALBERT F. MILLER, OF KANSAS CITY, KANSAS

JOINT LOCK

Application filed August 24, 1928. Serial No. 301,787.

My invention relates to improvements in joint locks. It is an improvement on the joint lock invention for which Letters Patent Number 1,376,150 were issued to me on April 26, 1921. It is particularly well adapted for use in the construction of grille-work for fastening bars to rails and for fastening together two rails.

One of the objects of my invention is to provide a novel, simple, cheap and efficient joint lock, which is strong, durable, not liable to break or get out of order, which can be easily and quickly assembled or disassembled, and which presents a neat and attractive appearance.

A further object of my invention is to provide a novel means for fastening together two rails disposed at an angle to each other.

Still another object of my invention is to provide a light structure, the parts composing which may have a maximum of strength for a minimum of weight and which may separately be cheaply made from rolled or drawn stock.

25 The novel features of my invention are hereinafter fully described and claimed.

In the accompanying drawing, which illustrates the preferred embodiment of my invention,

30 Fig. 1 is a perspective view of grille-work embodying my invention.

Fig. 2 is a perspective view of one of the bars.

Fig. 3 is a perspective view of one of the 35 slot closing plates.

Fig. 4 is a longitudinal vertical section of a portion of what is shown in Fig. 1.

Fig. 5 is an enlarged section on the line 5—5 of Fig. 4.

40 Fig. 6 is an enlarged section on the line 6—6 of Fig. 4.

Similar reference characters designate similar parts in the different views.

The grille-work shown in Figs. 1 and 4, is 45 provided with two horizontal parallel tubular rails disposed one above the other, and which are connected to each other by vertical tubular bars 1.

The top rail and the bottom rail differ 50 only in their positions, which are reversed.

The top rail and bottom rail each comprises a horizontal tube 2, having in one side a longitudinal slot 3, the slot in the upper tube 2 being in its upper side, and the slot 3 of the lower tube being in its bottom side. Two longitudinal plates 4 are respectively mounted in the tubes 2, the upper plate 4 having a bearing against the under side of the top of the upper tube 2, and the lower plate 4 bearing against the top of the bottom of the lower 60 tube 2.

Each of the plates 4 is provided with a central longitudinal rib 5 fitted in and filling the adjacent slot 3.

The bottom of the upper tube 2 and the top 65 of the lower tube 2 are each provided with a longitudinal row of holes 6, which may be square and of different sizes, as shown.

The upper ends of the tubular bars 1 extend through the holes 6 in the upper tube 2 70 and bear against the under side of the adjacent plate 4, thereby holding the latter in its proper position. The lower ends of the bars 1 extend through and are fitted in the holes 6 in the lower tube 2, and bear against the 75 upper side of the adjacent plate 4.

Two longitudinal locking bars 7 are respectively mounted in the upper and lower tubes 2.

The bars 1 within the upper tube 2, are 80 each provided with a perforation 8 disposed parallel with the upper tube 2 and closely adjacent to the bottom thereof.

The bars 1 within the lower tube 2 are similarly provided with similar perforations 85 8 disposed closely adjacent to the upper side of the lower tube 2.

The perforations 8 in the upper tube 2 align with each other, as do the perforations 8 in the lower tube 2.

40 The locking bars 7 extend through and are respectively removably fitted in the perforations 8 in the end portions of all of the bars 1, excepting the bar 1 adjacent to the right ends of the tubes 2, as viewed in Figs. 1 and 95 2. The upper bar 7 bears against the upper side of the bottom of the upper tube 2. The lower bar 7 bears against the under side of the top of the lower tube 2. The locking bars 7 thus securely fasten, to the upper 100

and lower rails, the bars 1 with which they are associated.

At the end of the grille-work may be provided a vertical stile having mitered connection at its upper and lower ends respectively with the upper and lower rails.

Said stile comprises a vertical tube, 9, similar in shape, width and thickness to the rail tubes 2, and provided in its outer side 10 with a vertical slot 10, Fig. 6, in which is fitted the central longitudinal rib 5 of a plate 4, corresponding to those already described, which bears against the outer side of the tube 9.

15 Two angle members 11 have one set of arms mounted in the tube 9 at opposite ends thereof respectively, the other two arms of said members being respectively fitted in the adjacent ends of the upper and lower tubes 2.

20 The perforations 8 in the bar 1 which is next adjacent to the tube 9 are screw threaded and have respectively fitted in them two screws 12 which extend longitudinally in the tubes 2 respectively, and which are respectively mounted in holes provided in the angle members 11.

25 The screws 12 also respectively extend through holes provided in the vertical plate 4 and have their heads bearing against the outer side of said plate. The screws 12 releasably hold the bar 1 with which they engage firmly in its proper position.

In assembling the grille-work, shown in Figs. 1 and 4, the bars 1 are all inserted in the 30 holes 6 of the tubes 2, with the perforations 8 alined with each other in said tubes, after which the bars 7 are respectively inserted in the tubes 2 and through the adjacent perforations 8 of those bars 1 which they are designated to lock in position. The plates 4 are then 35 respectively slid across the adjacent ends of the bars 1 into their proper positions in the slots 3 of the tubes 2.

40 The angle members 11 are then mounted in the tube 9, after which the vertical plate 4 is slid into the slot 10 of the tube 9, following which the angle members 11 are respectively inserted into the tubes 2. The screws 12 are then inserted through the vertical plate 4 and 45 the angle members 11, after which the screws are fitted respectively into the holes 8 of the adjacent bar 1.

50 A similar stile may be similarly attached to the opposite end of the grille-work, is so desired.

55 In adapting the parts for any particular use, the bars 1 may be of any desired form and diameter, and the holes 6 in the tubes 2 may be of such form and size as may be required for the bars 1 employed, and such holes may be spaced apart to suit the distance desired between the bars 1. The tubes 2 and plates 4 may be made by rolling or drawing, and may be separately made and sold for 60 stock purposes. In such cases the user may

provide in the tubes 2 holes 6 to meet his particular requirements.

I do not limit my invention to the structure shown and described, as many modifications, within the scope of the appended claims, may be made without departing from the spirit of 70 my invention.

What I claim is:—

1. In a joint lock of the kind described, a tubular rail having in one side a hole, a bar 75 extending through said hole and bearing against the opposite side of said rail and having a transverse perforation therethrough located within said rail, and a locking member extending through and projecting from said perforation and bearing against the side of the rail having said hole.

2. In a joint lock of the kind described, a tubular rail having in one side a row of holes, bars extending respectively through 80 said holes and bearing against the opposite side of said rail and provided each within said rail with a perforation, said perforations alining with each other, and a locking member extending through said perforations and bearing against the side of the rail having 85 the holes.

3. In a joint lock of the kind described, a tubular rail comprising a tube having in one side a longitudinal slot and provided in the 90 opposite side with a hole, and a plate in said tube closing said slot, a bar extending through said hole and bearing against said plate and having a transverse perforation within said tube, and a locking member extending through said perforation and bearing against the side of said tube having said hole.

4. In a joint lock of the kind described, a tubular rail comprising a tube having in one side a longitudinal slot and provided in the 95 opposite side with a row of holes, and a plate in said tube closing said slot, bars extending respectively through said holes and bearing against said plate and having each a transverse perforation in said tube, said perforations alining with each other, and a locking member extending through said perforations and bearing against the side of said tube having 100 said holes.

5. In a joint lock of the kind described, a 105 tubular rail having in one side a hole, a bar extending through said hole and bearing against the opposite side of said rail and having within said rail a transverse threaded perforation, a member closing one end of 110 said rail, and a screw extending through and having a bearing against said member and fitted in said perforation.

6. In a joint lock of the kind described, a 115 tubular rail comprising a tube having in one side a longitudinal slot and in the opposite side having a hole, and a plate in said tube closing said slot, a bar extending through 120 said hole and bearing against said plate and having within said tube a transverse threaded 125 member closing one end of said rail, and a screw extending through and having a bearing against said member and fitted in said perforation.

perforation, and a screw fitted in said perforation and bearing against the side of the tube having said hole.

7. In a joint lock of the kind described, a tubular rail comprising a tube having in one side a longitudinal slot and having in the opposite side a hole, and a plate in said tube closing said slot, a bar extending through said hole and bearing against said plate and having within said tube a transverse threaded perforation, a member closing one end of said rail, and a screw extending through said member and fitted in said perforation and bearing against the side of the tube having said hole.

8. In a joint lock of the kind described, a tubular rail having in one side a hole, a bar extending through said hole and bearing against the opposite side of said rail and having within said rail a transverse threaded hole, a screw fitted in said threaded hole and bearing against the side of said rail having therein the first named hole, and a second rail at an angle to and closing one end of the first named rail and through which said screw extends and has a bearing.

9. In a joint lock of the kind described, a tubular rail having on one side a hole, a bar extending through said hole and bearing against the opposite side of said rail and having a transverse threaded perforation located within said rail, a screw fitted in said perforation, a tubular rail at an angle to and closing the first named rail, and an angle member having its arms respectively fitted in said rails, said screw extending through and having a bearing against the second named rail.

In testimony whereof I have signed my name to this specification.

ALBERT F. MILLER.
